WRENCH

Original Filed April 8, 1922

UNITED STATES PATENT OFFICE.

THOMAS H. ROSS, OF BROOKLYN, NEW YORK, ASSIGNEE OF ONE-HALF TO ROBERT K. STORY, OF NEW YORK, N. Y.

WRENCH.

Application filed April 8, 1922, Serial No. 550,766. Renewed January 31, 1924.

To all whom it may concern:

Be it known that I, THOMAS H. Ross, a citizen of the United States, and resident of the borough of Brooklyn, in the county 5 of Kings and State of New York, have invented certain new and useful Improvements in Wrenches, of which the following is a clear and exact specification, reference being had to the drawing, which forms a part 10 of this specification.

This invention relates to wrenches, and my improvements are directed to a certain novel construction and interacting relation of object engaging parts whereby in the 15 movement of a wrench in one direction an engaged object is gripped with increasing tenacity, utilizing the head portion of the wrench as a fulcrum, while in its opposite direction of movement the engaging parts of 20 the wrench are relaxed to release and pass freely about the object.

For these purposes my invention consists of a handle or stock in whose head portion there is pivotally held a jaw that extends 25 angularly therefrom, this pivotal jaw having an angular extension; another jaw, opposed to the pivotal jaw, also having an angular extension, the angular extensions of both jaws being in interfitting slidable relation, and having their respective fulcra 30 upon the head portion of the wrench stock.

The jaws are normally urged toward each other under moderate spring pressure to accord them initial engaging contact upon 35 an interposed work-object, but the gripping action of the jaws upon the work-object is acquired by movement of the stock in one direction, in which operation the head portion of the stock provides separate fulcra 40 to press the jaws more tightly upon the work-object; whereas movement of the stock in the opposite direction has the effect of releasing the grip of the jaws, permitting them to slip freely over the work-object 45 preparatory to applying another turn thereto.

The arrangement whereby the jaws are in slidable interfitting relation includes the provision that as they press oppositely upon 50 an interposed work object the jaws are en-

abled to rock slightly in their plane of movement giving them the tendency to embrace the work-object, and thereby enhancing the security of the grip with which it is held.

Other features and advantages of my invention will hereinafter appear. 55

In the drawings:—

Figure 1 is a side elevation of my improved wrench, the handle or stock thereof 60 being shown as broken away.

Fig. 2 is a similar view illustrating the jaws gripped upon an interposed work object.

Fig. 3 is a front view of the wrench.

Fig. 4 is a side elevation of the slidable 65 jaw.

Fig. 5 is a rear view thereof.

Fig. 6 is a side elevation of the pivoted jaw, and

Fig. 7 is a rear view thereof. 70

In the figures let the numeral 1 indicate the wrench handle or stock, having the bifurcated head portion 2 which has the pivotal pin 3, and the terminal, peripheral, arcuate-surfaces 4 that are in concentric relation to pin 3, and that intersect, rearwardly of the transverse plane occupied by the pin, respectively with the arcuate-surfaces 5 and 6 upon the front and rear of the head portion. 75

One of the wrench jaws 7, is journaled on pin 3, and this jaw, for purposes of identification, will be hereinafter referred to as the pivotal jaw. This jaw 7 has the face or object gripping portion 8, the reduced portion 80 9 to enter between the bifurcations of head portion 2, where it is engaged by pin 3, and the further reduced, angular extension 10, having base flanges 11. 85

It will be noted that the flanges 11, at 90 each side of portion 10, are, for a portion of their extent, in parallelism with the shoulders 12 formed by portion 9, and that angled surfaces 13 of flanges 11 are in parallelism with angular extensions 14 of shoulders 12. The significance of these features 95 will appear hereinafter in the description of the operation of the wrench.

It should also be noted that the angular extension 10 is provided with a longitudinal 100

slot 15. The rear surfaces of the object gripping portion 8 will be seen to have segmental parts 16^a, which co-act with the peripheral surfaces 4 of the stock.

5 The other jaw, 16, has the gripping portion 17 and an angular, bifurcated extension comprising the parallel spaced members 18, which are reduced at their outer surfaces to provide recesses 19, the shoulders at one 10 end of each recess having the angular surfaces 20, 21 and 22, and the shoulders at the other end of each recess having the angular surfaces 23, 24 and 25.

15 The recesses 19 are adapted, respectively, to receive the bifurcated head-portion 2, whose arcuate-surfaces 5 and 6 respectively co-act with the surfaces 23 and 20; the head-surfaces 4 co-acting with surfaces 21 and 24, which serve as stops, and the wrench-stock 20 co-acting with surfaces 22, 25, which also serve as stops.

25 The space between members 19 is adapted for the reception of the extension 10 of jaw 7, in order that the extensions 10 and 18 may interfit in slidable relation. The opposed inner surfaces of recesses 19 are provided with grooves 26, to contain a helical spring 27 which, in the interfitted relation of the jaws, also lies within the slot 15 of 30 extension 10. A pin 28, secured within the members 18, serves as an anchorage for one end of spring 27, whose opposite end bears tensionally against the end 29 of slot 15.

35 The gripping portions of the jaws 7 and 16 are represented as being normally in substantially parallel, spaced relation, the teeth of portion 8 being inclined outwardly, and the teeth of portion 17 being inclined inwardly. Therefore these respective teeth 40 tend to bite engagingly into the respective surfaces of an interposed work-object, with which they contact in a direction opposite to the direction of resistance, to thus more effectually grip such object, whilst also 45 permitting the teeth to more smoothly glide over the surface of the work-object, to release it, when the wrench is turned in the opposite direction.

50 It will be observed that while the jaw 7 is journalled on pin 3, its fulcrum is provided by the head of the stock, whose end peripheral surfaces 4 co-act with the concaved seats 16^a behind the jaw face, so that when the jaws 7 and 16 grip a work object, as 55 shown at 30 in Fig. 2, the wrench being swung in the direction of the arrow, relative concentric oscillatory movement only will be possible between the jaw 7 and head 2.

60 The jaw 16 is not journalled at all in the head 2, being as stated, slidably interfitting with jaw 7; but jaw 16 also has its fulcrum provided by the head 2, because, by means of its recesses 19 formed in the 65 respective outer sides of members 18, seats

are instituted for the reception of those portions of head 2 which include the curved-surfaces 5 and 6, whereby the shoulder-surfaces 20 co-act with the arcuate-surfaces 6, and the shoulder surfaces 23 co-act with the 70 arcuate-surfaces 5.

75 In the operation of my improved wrench, with a work-object, such for example as a pipe 30, interposed between the jaws 7, 16, the effect is as follows:—

The spring 27 is provided for the purpose of extending the extensions 10, 18 to the limit of their movement, which is determined by the engagement of surface 25 with the stock, thus causing the jaw portions 8, 80 17 to be drawn toward each other to reduce the extent of their work-object receiving gap to the minimum. The wrench is shown in this condition in Fig. 1. Then the jaws, as will be perceived, by reason of the curved 85 lips upon their jaw portions 8, 17 may, by pressure against the work-object, yield apart, against the tension of the spring, to receive the work-object.

90 The spring pressure with which the teeth of the jaws engage the work object provides only initial contact, and is merely intended to automatically adjust the wrench jaws to their operative position about the work-object.

95 As thus adjusted, pressure is then to be applied to the stock 1 in the direction of the arrow, (Fig. 2) which has the effect of causing the jaws to grip the work object with increasing tenacity as the pressure is amplified for the purpose of turning the work-object.

100 In this action the stock head surfaces 4 provide a constant bearing for the jaw 7 at its segmental seats 16^a, while the curved 105 peripheral surfaces 5 of the stock, co-acting with the bearings 23 on extensions 18 of the jaw 16, thereby apply the leverage which enables the jaws to exercise the powerful gripping hold upon the work-object that is 110 characteristic of my improved wrench.

115 Also, it must be particularly noted that as the gripping leverage is applied upon the work-object in the manner indicated, the jaw 7 is capable of rocking inwardly toward the jaw 16 on account of the inclined deviations 13 and 14 respectively from the lines of its slide bearings 12 and flanges 11, which thus afford slack or play, whose take up under pressure of the leverage, permits 120 the gripping stress to be exerted in inwardly angled lines of force from the respective jaws. There is thus constituted a partial girdling or embracing grip of great power, whereby any screw joint may be 125 turned.

130 In order to obtain a new purchase of the work-object the wrench is merely swung in the reverse direction, in which it will have no gripping action, the jaw teeth slipping

freely over the work-object, in preparation for applying a further power turn. In this action the arcuate-surfaces 6 bear against the seats 20, thus spreading the jaws apart.

5 The serrations 31 upon one end of extension 10 are provided for the application of thumb pressure, while grasping the stock with one hand, to spread apart the jaws against the tension of spring 27, in fitting 10 the wrench to the work-object and in withdrawing it therefrom.

The serrations 32, outside jaw portion 17 may be desirable for large sized wrenches, when the spring 27 is more powerful, in order 15 that the serrated surfaces 31 and 32 may be grasped between the thumb and fingers of the free hand to expand the jaws.

Variations within the spirit and scope of my invention are equally comprehended by 20 the foregoing disclosure.

I claim:—

1. A wrench comprising a stock, a pivot, carried thereby, a jaw mounted on the pivot, and a complementary jaw slidably mounted 25 on the stock, behind the pivot, the stock having peripheral bearing surfaces in separate transverse planes respectively through the pivot and rearwardly thereof, which co-act directly with the jaws to apply gripping leverage thereto.

2. A wrench having in combination a stock with a bifurcated head, a pivot carried by the head, a jaw mounted on the pivot in the head, and a complementary jaw lying 35 within the head in slidable relation to the pivotal jaw, the head having peripheral bearing surfaces in separate transverse planes, respectively through the pivot and rearwardly thereof, which co-act directly with 40 the jaws to apply gripping leverage thereto.

3. A wrench having in combination a stock, a jaw pivotally mounted thereon, and a complementary jaw in longitudinally slid- 45 able relation to the pivotal jaw, the stock having bearing surfaces which co-act with the jaws to apply gripping leverage thereto, and the jaws being provided with means of relative lateral movement, permitting their lines of gripping force to be exerted in in- 50 ward angles.

4. A wrench having in combination a stock with a bifurcated head, a pivot carried by the head, a jaw mounted on the pivot in the head, a complementary jaw lying 55 within the head in slidable relation to the pivotal jaw, the head having peripheral bearing surfaces in separate transverse planes, respectively through the pivot and rearwardly thereof, which co-act directly with 60 the jaws to apply gripping leverage thereto, and tensional means to normally urge the jaws toward each other to establish their initial contact with an interposed work-object.

65 5. A wrench comprising in combination a

stock with a bifurcated head, having an end arcuate bearing and a rearward arcuate bearing, a jaw pivotally held in the head, the jaw having a gripping face portion, and a rearward surface to co-act with the end 70 arcuate bearing on the stock, the jaw also having a rearward, reduced portion whereby it is pivotally mounted in the head, and having an angular extension; and a complementary jaw opposed to the pivotal jaw having 75 an angular extension in interfitting slid- able relation with the angular extension of the pivotal jaw, the slidable jaw coacting with the rearward arcuate bearing on the head for the application of gripping pres- 80 sure between the jaws upon swinging the stock about a work object.

6. A wrench comprising in combination, a stock with a bifurcated head, having an end arcuate bearing and a rearward arcuate bearing, a jaw pivotally held in the head, the jaw having a gripping face portion, and a rearward surface to co-act with the end 85 arcuate bearing on the stock, the jaw also having a rearward, reduced portion whereby it is pivotally mounted in the head, and having an angular extension; a complementary jaw opposed to the pivotal jaw having an angular extension in interfitting slid- able relation with the angular extension of 90 the pivotal jaw, the slidable jaw co-acting with the rearward arcuate bearing on the head for the application of gripping pres- 95 sure between the jaws upon swinging the stock about a work object, and the extensions 100 having lateral, angled clearances in their interfitted relation which enable the jaws to rock in object embracing manner under the application of gripping stress.

7. A wrench comprising a pair of opposed 105 jaws having angled extensions in interfitting, mutually slidable relation, a stock, and a pivot holding one of the jaws to the stock, the pivotal jaw having a seat behind its work-face to co-act with the peripheral end 110 of the stock in the transverse plane of the pivot, and the other jaw having a seat on its extension to also co-act with the stock, rearwardly of the pivot.

8. A wrench comprising a pair of opposed 115 jaws having angled extensions in interfitting, mutually slidable relation, a stock, and a pivot holding one of the jaws to the stock, the pivotal jaw having a seat behind its work-face to co-act with the peripheral end 120 of the stock in the transverse plane of the pivot, the other jaw having a seat on its extension to also co-act with the stock, rearwardly of the pivot, and a spring whose ten- 125 sion is exerted upon the jaw extensions to urge the jaws normally toward each other.

9. A wrench comprising a pair of opposed jaws having angled extensions in interfitting, mutually slidable relation, a stock, and a pivot holding one of the jaws upon the 130

stock, the pivotal jaw having a seat behind its work-face to co-act with the peripheral end of the stock, in the transverse plane of the pivot, and the other jaw having a seat on its extension to also co-act with the stock rearwardly of the pivot, the jaw extensions having lateral, angled clearances to permit

inward locking motion to the jaws in their gripping operation.

Signed at the borough of Manhattan, in the city, county and State of New York, this 4th day of April 1922.

THOMAS H. ROSS.
